United States Patent Office

Des. 223,650
Patented May 23, 1972

223,650

SASH

Melvin V. Zakarin, 23 Ogden Lane,
Englishtown, N.J. 07726

Filed July 20, 1970, Ser. No. 24,016

Term of patent 3½ years

Int. Cl. D2—07

U.S. Cl. D2—385

Fig. 1.

Fig. 2.

Fig. 3.

Fig. 4

FIG. 1 is a front perspective view of a sash showing my new design, the decorative design unit being repeated the length of the sash as indicated;

FIG. 2 is a front plan view thereof shown broken away for convenience of illustration;

FIG. 3 is a rear plan view thereof; and

I claim:

The ornamental design for a sash, substantially as shown and described.
